D20-32

EX

OR D 12,892

No, 12,892.

Apr. 18. 1882.

UNITED STATES PATENT OFFICE.

ELHANAN L. MOODIE, OF NEW YORK, N. Y., ASSIGNOR OF ONE-HALF TO
CHARLES H. GILLESPIE, OF SAME PLACE.

DESIGN FOR AN ADVERTISING OR ORNAMENTAL DISK OR PLATE.

SPECIFICATION forming part of Design No. 12,892, dated April 18, 1862.

Application filed March 14, 1862. Term of patent 3½ years.

To all whom it may concern:

Be it known that I, ELHANAN L. MOODIE, a citizen of the United States, residing in the city and county of New York, in the State of New York, have invented and produced a new and original Design for Advertising or Ornamental Disks or Plates, of which the following is a specification, reference being had to the accompanying drawing or photographic representation, forming part thereof.

This invention consists in a novel design for a plate or disk to be used for ornamental or advertising purposes. When used for advertising purposes there may be printed or otherwise marked or affixed thereon any suitable advertising matter.

The leading feature of my design consists in an ornamental or advertising disk or plate having upon its face the representation of a human face surmounted and to a certain extent surrounded by the representation of a "Gainsborough" hat, so called, the circumference of the disk corresponding in form and contour to the circumference of the representation of the Gainsborough hat aforesaid, saving and excepting that part which forms the lower portion or neck of the representation of the human face or head. The representation of the human face or head, as shown in the photographic portraiture or representation above referred to, is apparent without the use of a reference-letter. Above and around this is the representation A of a Gainsborough hat, as seen from the front, and the disk or plate

itself has a circumferential contour corresponding to the circumferential contour of the representation of the Gainsborough hat, saving and excepting at the lower part, coincident with the neck or lower portion of the representation of the human face, at which preferably is the representation of a ruffle or other neck-wear.

It will be seen that the disk or plate embodying said design presents to the eye the combined effect of a human face surmounted and, so to speak, surrounded by a Gainsborough hat, the circumference of said plate corresponding, as aforesaid, substantially to the circumference of the representation of the said hat.

It is of course to be understood that the representation of the face and also the representation of the hat may be tinted or colored in any desired or appropriate manner.

What I claim as my invention is—

The design for an advertising or ornamental disk or plate composed of the representation of a human face surmounted and surrounded by the representation of a Gainsborough hat and having its circumferential contour substantially identical with that of the said representation of the hat, substantially as set forth.

ELHANAN L. MOODIE.
